(57) **CLAIM**

The ornamental design for a tree stand, as shown and described.

DESCRIPTION

FIG. 1 is a perspective view of a tree stand;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is another perspective view thereof, shown in a state of use.

The dashed broken lines in the figures illustrate portions of the tree stand that form no part of the claimed design. The dot-dash lines represent a boundary and form no part of the claimed design. The broken lines in FIG. 8 that show a tree represents environmental subject matter only and form no part of the claimed design.

1 Claim, 8 Drawing Sheets
